APPARATUS FOR COOLING OR FREEZING

Michael H. Ackerman, Mansfield, Ohio, assignor
to The H. H. Miller Industries Company,
Canton, Ohio, a corporation of Ohio

Application May 30, 1933, Serial No. 673,719

17 Claims. (Cl. 62—114)

This invention relates to apparatus for applying a volatile liquid refrigerant to the walls of an evaporator adapted to receive and hold liquids or semi-liquids from which heat is to be extracted in such manner that thermal siphon refrigerant circulation means are entirely eliminated, insulating conditions due to the formation of gas pockets on the evaporator walls are prevented, rapid separation of the generated gases from the liquid refrigerant is effected and unobstructed upward flow of the separated gases is provided for. In the use of the term evaporator I comprehend receptacles forming parts of various apparatus, such as pasteurizers, holders, coolers and freezing mechanisms, one of the latter mechanisms being chosen as showing the preferred application of my invention.

The illustrated construction embodying my present invention effects freezing of "mixes" in an evaporator by the direct application to its walls of a volatile liquid refrigerant, which is circulated by mechanical means in a manner to cause the refrigerant to flow at a relatively rapid rate over and in continuous intimate contact with the evaporator walls, as long as heat transfer is required.

One object of the present invention is to simplify the construction shown in my co-pending application Ser. No. 565,425, filed September 28, 1931.

Another object of the invention is to provide an insulated casing having incorporated therein an evaporator in spaced relation to the walls of the casing so as to effect automatically separation of the liquid refrigerant from the gases generated by the transfer of heat through the walls of the evaporator.

Another object of the invention is to provide an improved evaporator enclosing casing for a volatile liquid refrigerant and incorporating therewithin an evaporator and means for applying to or cutting off the supply of the refrigerant from the walls of the evaporator, whereby thermal siphonic circulation or flooding of the refrigerant into and out of the enclosing casing is eliminated.

Another object of the invention is to provide an improved freezing or cooling mechanism using a volatile liquid refrigerant and comprising a casing serving as an enclosure for an evaporator, an accumulator for the refrigerant and a gas separator and as a means in connection with a liquid distributing device above the evaporator for applying the liquid refrigerant to the latter, the evaporator being enclosed within the casing in spaced relation to its walls but above the level

of the refrigerant therein, whereby the refrigerant freely flows over the evaporator walls and automatically scours therefrom resulting gas pockets or bubbles and insures separation of the latter from the liquid. This arrangement and 60 operation or process provides for the rapid transfer of heat units through the evaporator walls.

Another object of the invention is to provide an improved freezing or cooling mechanism using a volatile liquid refrigerant and comprising a 65 closed casing for the refrigerant and an evaporator within the casing in such relation to the supply of refrigerant therein that the refrigerant may be readily utilized to effect or cut off the heat transfer, whereby successive batches of material may be rapidly treated without delay between them.

Another object of the invention is to provide an improved freezing or cooling mechanism using volatile liquid as a refrigerant and comprising a 75 closed casing connected to a suction pipe and forming an accumulator for a substantially predetermined supply of the liquid and a gas separator, means for elevating the liquid within the casing to the space above its normal level and a material holding evaporator disposed in the path of the gravitating liquid but above its normal level, whereby the walls of the evaporator are washed by the liquid to maintain them free of gas pockets or bubbles.

Another object of the invention is to provide an improved freezing or cooling mechanism for liquid material using a volatile liquid as a refrigerant and comprising a closed casing for the liquid and a material holding evaporator therein 90 and means for readily applying or cutting off refrigeration to the walls of the evaporator without removal of the liquid from the casing.

Another object of the invention is to provide an improved material freezing or cooling mechanism using a volatile liquid as a refrigerant in which the liquid holding casing and material holding evaporator and liquid circulating means are combined in a unitary structure, whereby its walls may be effectively insulated to eliminate 100 exposed parts that would otherwise become frosted and wasted refrigeration.

Another object of the invention is to incorporate with the evaporator casing improved means for separating from the liquid refrigerant 105 any lubricant which may collect in the refrigerant.

Other objects of the invention will be apparent to those skilled in the art to which my invention relates from the following description 110

taken in connection with the accompanying drawings, wherein

Fig. 1 is a view of a freezing or cooling mechanism embodying my invention, partly in elevation and partly in section on the line 1—1 of Fig. 2.

Fig. 2 is a section on the line 2—2 of Fig. 1.

Fig. 2a is a section on the line 2a—2a of Fig. 1.

Fig. 3 is a fragmentary section substantially on the line 3—3 of Fig. 1, enlarged.

Fig. 4 is a fragmentary section on the line 4—4 of Fig. 1, enlarged.

Fig. 5 is a view similar to Fig. 1 but embodying a different form of liquid refrigerant elevating and distributing means.

Fig. 6 is a section on the line 6—6 of Fig. 5.

Referring to Figs. 1, 2, 3 and 4 of the drawings, 1 indicates a support comprising a hollow casting preferably having a flaring base 1a, a rear portion forming a bed 1b and a forwardly extending case 1c. The purpose of the bed 1b and 1c will later appear.

2 indicates as an entirety an evaporator which, in the present disclosure, is adapted to contain material from which heat is to be extracted, for example, in making ice cream, ices and similar products; such container and the agitating mechanism therein being preferably applicable for freezing such products in successive batches.

30 The evaporator 2 comprises a cylinder 2a having a rear head 2b and a front head 2c. The cylinder 2a may be centrifugally cast from suitable metal or formed from a plate of suitable material rolled into cylindrical form. The walls of the cylinder 35 are of a thickness to resist external pressure.

The inner end of the cylinder 2a is secured liquid-tight in any desired manner to the rear head 2b. The rear head is suitably secured to the bed 1b. The front head 2c is removably secured in 40 a liquid tight manner to an annular seat provided on a substantially annular member 2d.

The member 2d consists of a ring 2e carrying the annular seat and surrounded by a plate 2f, the lower portion of which is suitably secured to 45 the front wall 1c' of the case 1c, such connection and the connection of the rear head 2b to the bed 1b serving to mount the evaporator 2 on the support 1 and also other parts hereinafter referred to. The rear head 2b is provided with 50 an inlet duct 3 connected with a valve controlled supply pipe 4 leading from a suitable measuring tank 4a. The front head 2c is provided with a valve controlled outlet 5. The head 2c may be constructed and removably mounted as shown in Letters Patent No. 1,449,623, granted to Leroy S. Pfouts.

60 6 indicates an agitating and ejecting mechanism within the cylinder 2a and preferably comprising inner and outer rotatable members, the outer member comprising spiders carrying suitable scrapers 7 and one or more ejecting elements 7a and the inner member comprising a shaft 9 carrying propelling blades 7b. The spiders rotate on the shaft 9, the inner spider being connected to a shaft 10. The agitating and ejecting mechanism is preferably constructed similar to that shown in Letters Patent No. 1,692,964. The outer end of the shaft 9 is suitably mounted in the front head 2c. The two shafts 9, 10, extend through the rear head 2b

70 and are driven in a well known manner by a suitable driving mechanism 8. The driving mechanism 8 is suitably mounted on the bed 1b and consists of an electric motor 8' the shaft of which operates through suitable reduction gearing, within the casing 8x, to drive gears within

the gear box 8x'. The gears are connected to the shafts 9, 10, which in turn are connected to the inner end and outer rotatable members of the mechanism 6 to rotate them in opposite directions.

11 indicates as an entirety an evaporator enclosing casing the purpose of which is to serve as an accumulator for a predetermined supply of a volatile liquid refrigerant, such as liquid ammonia, and a gas separator.

12 indicates as an entirety means for elevating the refrigerant above the evaporator and distributing it thereon, whereby its cycle of circulation and application are controlled.

In the present application of my invention, the casing 11 surrounds the side walls or body of the evaporator in spaced relation thereto, leaving the rear and front heads 2b, 2c, exposed, so that the supply of the "mix" or material to the evaporator and its discharge therefrom, application of mechanical power to the agitating mechanism 6 and removal and replacement of the agitating mechanism, are provided

for in a simplified manner, independently of the casing 11, and storing and circulation of the refrigerant.

The casing 11 comprises a body 11a or 90 or 95 or 100 or 105 or 110 or 115 or 120 or 125 or 130 or 135 or 140 or 145 or 150

or 111 or 112 or 113 or 114 or 115 or 116 or 117 or 118 or 119 or 121 or 122 or 123 or 124 or 125 or 126 or 127 or 128 or 129 or 130 or 131 or 132 or 133 or 134 or 135 or 136 or 137 or 138 or 139 or 140 or 141 or 142 or 143 or 144 or 145 or 146 or 147 or 148 or 149 or 150 or 151 or 152 or 153 or 154 or 155 or 156 or 157 or 158 or 159 or 160 or 161 or 162 or 163 or 164 or 165 or 166 or 167 or 168 or 169 or 170 or 171 or 172 or 173 or 174 or 175 or 176 or 177 or 178 or 179 or 180 or 181 or 182 or 183 or 184 or 185 or 186 or 187 or 188 or 189 or 190 or 191 or 192 or 193 or 194 or 195 or 196 or 197 or 198 or 199 or 200 or 201 or 202 or 203 or 204 or 205 or 206 or 207 or 208 or 209 or 210 or 211 or 212 or 213 or 214 or 215 or 216 or 217 or 218 or 219 or 220 or 221 or 222 or 223 or 224 or 225 or 226 or 227 or 228 or 229 or 230 or 231 or 232 or 233 or 234 or 235 or 236 or 237 or 238 or 239 or 240 or 241 or 242 or 243 or 244 or 245 or 246 or 247 or 248 or 249 or 250 or 251 or 252 or 253 or 254 or 255 or 256 or 257 or 258 or 259 or 260 or 261 or 262 or 263 or 264 or 265 or 266 or 267 or 268 or 269 or 270 or 271 or 272 or 273 or 274 or 275 or 276 or 277 or 278 or 279 or 280 or 281 or 282 or 283 or 284 or 285 or 286 or 287 or 288 or 289 or 290 or 291 or 292 or 293 or 294 or 295 or 296 or 297 or 298 or 299 or 300 or 301 or 302 or 303 or 304 or 305 or 306 or 307 or 308 or 309 or 310 or 311 or 312 or 313 or 314 or 315 or 316 or 317 or 318 or 319 or 320 or 321 or 322 or 323 or 324 or 325 or 326 or 327 or 328 or 329 or 330 or 331 or 332 or 333 or 334 or 335 or 336 or 337 or 338 or 339 or 340 or 341 or 342 or 343 or 344 or 345 or 346 or 347 or 348 or 349 or 350 or 351 or 352 or 353 or 354 or 355 or 356 or 357 or 358 or 359 or 360 or 361 or 362 or 363 or 364 or 365 or 366 or 367 or 368 or 369 or 370 or 371 or 372 or 373 or 374 or 375 or 376 or 377 or 378 or 379 or 380 or 381 or 382 or 383 or 384 or 385 or 386 or 387 or 388 or 389 or 390 or 391 or 392 or 393 or 394 or 395 or 396 or 397 or 398 or 399 or 400 or 401 or 402 or 403 or 404 or 405 or 406 or 407 or 408 or 409 or 410 or 411 or 412 or 413 or 414 or 415 or 416 or 417 or 418 or 419 or 420 or 421 or 422 or 423 or 424 or 425 or 426 or 427 or 428 or 429 or 430 or 431 or 432 or 433 or 434 or 435 or 436 or 437 or 438 or 439 or 440 or 441 or 442 or 443 or 444 or 445 or 446 or 447 or 448 or 449 or 450 or 451 or 452 or 453 or 454 or 455 or 456 or 457 or 458 or 459 or 460 or 461 or 462 or 463 or 464 or 465 or 466 or 467 or 468 or 469 or 470 or 471 or 472 or 473 or 474 or 475 or 476 or 477 or 478 or 479 or 480 or 481 or 482 or 483 or 484 or 485 or 486 or 487 or 488 or 489 or 490 or 491 or 492 or 493 or 494 or 495 or 496 or 497 or 498 or 499 or 500 or 501 or 502 or 503 or 504 or 505 or 506 or 507 or 508 or 509 or 510 or 511 or 512 or 513 or 514 or 515 or 516 or 517 or 518 or 519 or 520 or 521 or 522 or 523 or 524 or 525 or 526 or 527 or 528 or 529 or 530 or 531 or 532 or 533 or 534 or 535 or 536 or 537 or 538 or 539 or 540 or 541 or 542 or 543 or 544 or 545 or 546 or 547 or 548 or 549 or 550 or 551 or 552 or 553 or 554 or 555 or 556 or 557 or 558 or 559 or 560 or 561 or 562 or 563 or 564 or 565 or 566 or 567 or 568 or 569 or 570 or 571 or 572 or 573 or 574 or 575 or 576 or 577 or 578 or 579 or 580 or 581 or 582 or 583 or 584 or 585 or 586 or 587 or 588 or 589 or 590 or 591 or 592 or 593 or 594 or 595 or 596 or 597 or 598 or 599 or 600 or 601 or 602 or 603 or 604 or 605 or 606 or 607 or 608 or 609 or 610 or 611 or 612 or 613 or 614 or 615 or 616 or 617 or 618 or 619 or 620 or 621 or 622 or 623 or 624 or 625 or 626 or 627 or 628 or 629 or 630 or 631 or 632 or 633 or 634 or 635 or 636 or 637 or 638 or 639 or 640 or 641 or 642 or 643 or 644 or 645 or 646 or 647 or 648 or 649 or 650 or 651 or 652 or 653 or 654 or 655 or 656 or 657 or 658 or 659 or 660 or 661 or 662 or 663 or 664 or 665 or 666 or 667 or 668 or 669 or 670 or 671 or 672 or 673 or 674 or 675 or 676 or 677 or 678 or 679 or 680 or 681 or 682 or 683 or 684 or 685 or 686 or 687 or 688 or 689 or 690 or 691 or 692 or 693 or 694 or 695 or 696 or 697 or 698 or 699 or 700 or 701 or 702 or 703 or 704 or 705 or 706 or 707 or 708 or 709 or 710 or 711 or 712 or 713 or 714 or 715 or 716 or 717 or 718 or 719 or 720 or 721 or 722 or 723 or 724 or 725 or 726 or 727 or 728 or 729 or 730 or 731 or 732 or 733 or 734 or 735 or 736 or 737 or 738 or 739 or 740 or 741 or 742 or 743 or 744 or 745 or 746 or 747 or 748 or 749 or 750 or 751 or 752 or 753 or 754 or 755 or 756 or 757 or 758 or 759 or 760 or 761 or 762 or 763 or 764 or 765 or 766 or 767 or 768 or 769 or 770 or 771 or 772 or 773 or 774 or 775 or 776 or 777 or 778 or 779 or 780 or 781 or 782 or 783 or 784 or 785 or 786 or 787 or 788 or 789 or 790 or 791 or 792 or 793 or 794 or 795 or 796 or 797 or 798 or 799 or 800 or 801 or 802 or 803 or 804 or 805 or 806 or 807 or 808 or 809 or 8010 or 8011 or 8012 or 8013 or 8014 or 8015 or 8016 or 8017 or 8018 or 8019 or 8020 or 8021 or 8022 or 8023 or 8024 or 8025 or 8026 or 8027 or 8028 or 8029 or 8030 or 8031 or 8032 or 8033 or 8034 or 8035 or 8036 or 8037 or 8038 or 8039 or 8040 or 8041 or 8042 or 8043 or 8044 or 8045 or 8046 or 8047 or 8048 or 8049 or 8050 or 8051 or 8052 or 8053 or 8054 or 8055 or 8056 or 8057 or 8058 or 8059 or 8060 or 8061 or 8062 or 8063 or 8064 or 8065 or 8066 or 8067 or 8068 or 8069 or 8070 or 8071 or 8072 or 8073 or 8074 or 8075 or 8076 or 8077 or 8078 or 8079 or 8080 or 8081 or 8082 or 8083 or 8084 or 8085 or 8086 or 8087 or 8088 or 8089 or 8090 or 8091 or 8092 or 8093 or 8094 or 8095 or 8096 or 8097 or 8098 or 8099 or 80100 or 80101 or 80102 or 80103 or 80104 or 80105 or 80106 or 80107 or 80108 or 80109 or 80110 or 80111 or 80112 or 80113 or 80114 or 80115 or 80116 or 80117 or 80118 or 80119 or 80120 or 80121 or 80122 or 80123 or 80124 or 80125 or 80126 or 80127 or 80128 or 80129 or 80130 or 80131 or 80132 or 80133 or 80134 or 80135 or 80136 or 80137 or 80138 or 80139 or 80140 or 80141 or 80142 or 80143 or 80144 or 80145 or 80146 or 80147 or 80148 or 80149 or 80150 or 80151 or 80152 or 80153 or 80154 or 80155 or 80156 or 80157 or 80158 or 80159 or 80160 or 80161 or 80162 or 80163 or 80164 or 80165 or 80166 or 80167 or 80168 or 80169 or 80170 or 80171 or 80172 or 80173 or 80174 or 80175 or 80176 or 80177 or 80178 or 80179 or 80180 or 80181 or 80182 or 80183 or 80184 or 80185 or 80186 or 80187 or 80188 or 80189 or 80190 or 80191 or 80192 or 80193 or 80194 or 80195 or 80196 or 80197 or 80198 or 80199 or 80200 or 80201 or 80202 or 80203 or 80204 or 80205 or 80206 or 80207 or 80208 or 80209 or 80210 or 80211 or 80212 or 80213 or 80214 or 80215 or 80216 or 80217 or 80218 or 80219 or 80220 or 80221 or 80222 or 80223 or 80224 or 80225 or 80226 or 80227 or 80228 or 80229 or 80230 or 80231 or 80232 or 80233 or 80234 or 80235 or 80236 or 80237 or 80238 or 80239 or 80240 or 80241 or 80242 or 80243 or 80244 or 80245 or 80246 or 80247 or 80248 or 80249 or 80250 or 80251 or 80252 or 80253 or 80254 or 80255 or 80256 or 80257 or 80258 or 80259 or 80260 or 80261 or 80262 or 80263 or 80264 or 80265 or 80266 or 80267 or 80268 or 80269 or 80270 or 80271 or 80272 or 80273 or 80274 or 80275 or 80276 or 80277 or 80278 or 80279 or 80280 or 80281 or 80282 or 80283 or 80284 or 80285 or 80286 or 80287 or 80288 or 80289 or 80290 or 80291 or 80292 or 80293 or 80294 or 80295 or 80296 or 80297 or 80298 or 80299 or 80300 or 80301 or 80302 or 80303 or 80304 or 80305 or 80306 or 80307 or 80308 or 80309 or 80310 or 80311 or 80312 or 80313 or 80314 or 80315 or 80316 or 80317 or 80538 or 80539 or 80540 or 80541 or 80542 or 80543 or 80544 or 80545 or 80546 or 80547 or 80548 or 80549 or 80550 or 80551 or 80552 or 80553 or 80554 or 80555 or 80556 or 80557 or 80558 or 80559 or 80560 or 80561 or 80562 or 80563 or 80564 or 80565 or 80566 or 80567 or 80568 or 80569 or 80570 or 80571 or 80572 or 80573 or 80574 or 80575 or 80576 or 80577 or 80578 or 80579 or 80580 or 80581 or 80582 or 80583 or 80584 or 80585 or 80586 or 80587 or 80588 or 80589 or 80590 or 80591 or 80592 or 80593 or 80594 or 80595 or 80596 or 80597 or 80598 or 80599 or 80600 or 80601 or 80602 or 80603 or 80604 or 80605 or 80606 or 80607 or 80608 or 80609 or 80610 or 80611 or 80612 or 80613 or 80614 or 80615 or 80616 or 80617 or 80618 or 80619 or 80620 or 80621 or 80622 or 80623 or 80624 or 80625 or 80626 or 80627 or 80628 or 80629 or 80630 or 80631 or 80632 or 80633 or 80634 or 80635 or 80636 or 80637 or 80638 or 80639 or 80640 or 80641 or 80642 or 80643 or 80644 or 80645 or 80646 or 80647 or 80648 or 80649 or 80650 or 80651 or 80652 or 80653 or 80654 or 80655 or 80656 or 80657 or 80658 or 80659 or 80660 or 80661 or 80662 or 80663 or 80664 or 80665 or 80666 or 80667 or 80668 or 80669 or 80670 or 80671 or 80672 or 80673 or 80674 or 80675 or 80676 or 80677 or 80678 or 80679 or 80680 or 80681 or 80682 or 80683 or 80684 or 80685 or 80686 or 80687 or 80688 or 80689 or 80690 or 80691 or 80692 or 80693 or 80694 or 80695 or 80696 or 80697 or 80698 or 80699 or 80700 or 80701 or 80702 or 80703 or 80704 or 80705 or 80706 or 80707 or 80708 or 80709 or 80710 or 80711 or 80712 or 80713 or 80714 or 80715 or 80716 or 80717 or 80718 or 80719 or 80720 or 80721 or 80722 or 80723 or 80724 or 80725 or 80726 or 80727 or 80728 or 80729 or 80730 or 80731 or 80732 or 80733 or 80734 or 80735 or 80736 or 80737 or 80738 or 80739 or 80740 or 80741 or 80742 or 80743 or 80744 or 80745 or 80746 or 80747 or 80748 or 80749 or 80750 or 80751 or 80752 or 80753 or 80754 or 80755 or 80756 or 80757 or 80758 or 80759 or 80760 or 80761 or 80762 or 80763 or 80764 or 80765 or 80766 or 80767 or 80768 or 80769 or 80770 or 80771 or 80772 or 80773 or 80774 or 80775 or 80776 or 80777 or 80778 or 80779 or 80780 or 80781 or 80782 or 80783 or 80784 or 80785 or 80786 or 80787 or 80788 or 80789 or 80790 or 80791 or 80792 or 80793 or 80794 or 80795 or 80796 or 80797 or 80798 or 80799 or 80800 or 80801 or 80802 or 80803 or 80804 or 80805 or 80806 or 80807 or 80808 or 80809 or 80810 or 80811 or 80812 or 80813 or 80814 or 80815 or 80816 or 80817 or 80818 or 80819 or 80820 or 80821 or 80822 or 80823 or 80824 or 80825 or 80826 or 80827 or 80828 or 80829 or 80830 or 80831 or 80832 or 80833 or 80834 or 80835 or 80836 or 80837 or 80838 or 80839 or 80840 or 80841 or 80842 or 80843 or 80844 or 80845 or 80846 or 80847 or 80848 or 80849 or 80850 or 80851 or 80852 or 80853 or 80854 or 80855 or 80856 or 80857 or 80858 or 80859 or 80860 or 80861 or 80862 or 80863 or 80864 or 80865 or 80866 or 80867 or 80868 or 808

latter in turn being operated to close and open the circuit for the coil by a float mechanism, indicated as an entirety at 19. The pipe 16 may lead into the casing 11 at any desirable point, for example, above the oil separating means, indicated as an entirety at 11x, as shown in Figs. 1 and 2, or below such means as shown in Figs. 5 and 6. Of the float mechanism 19, 20 indicates a hollow member closed at its outer end by a head 21 and removably mounted in an opening formed in the end plate 11b, the marginal portions of the head being secured to the plate 11b by bolts. The inner end of the member 20 is provided with diametrically arranged lugs 22 having aligned threaded openings for threaded pins 23, which serve as trunnions for a rocker 24. The rocker consists of a sealed tube 25, in which the switch 18 is mounted, and a float 24a fixedly connected to the rocker by a rod 24'.

The outer end of the tube 25 is internally threaded to receive a plug 26 which is sealed by a gasket 27. The switch 18 is preferably of the mercoide type and the leads therefrom are carried through openings formed in the inner end wall of the tube 25 and pipes 28 to a point exterior of the casing 11, so that the leads and switch are protected or sealed from the liquid refrigerant. The inner ends of the pipes 28 are sealed in their openings by a gland compressed by threaded, hollow members 29 which, when tightened, connect the pipes to the end wall of the tube 25. The outer end portions of the tubes 28 extend through and are suitably sealed in openings formed in the head 21 in a similar manner by threaded, hollow, members 30. The weight of the float 24a is partially off-set or counterbalanced to the desired extent by weights 31, so that it will readily respond to the rise and fall of the refrigerant level. The tubes 28 are formed of slightly resilient material and are coiled in opposite directions so as to act in opposition to each other without affecting the normal operation of the float but tending to prevent undue movement thereof in either direction.

In the form of construction shown in Figs. 1 and 2, the refrigerant circulating and distributing means 12 comprises a pump 32, a distributing device 33 in the evaporator casing 11 above the cylinder 2a and a liquid connection or pipe 34 between the outlet from the pump and said distributing device.

The distributing device 33 comprises a hollow member disposed centrally above the container 2 and extending substantially from end to end thereof and formed on its lower side with ports or openings to direct or distribute the liquid refrigerant in spray form or in small streams uniformly onto the evaporator wall. Obviously, the wall of the device may be provided with one or more rows of openings; also, in place of openings, nozzles or nipples may be used. The front end of the distributing device 33 is closed by a removable plug 35 (threaded into the end of the device), which is provided with tool engaging means. The plate 2f is provided with an opening 2f' to permit access to the plug 35, such opening being closed by a suitable shutter. The rear end of the distributing device 33 is connected by an elbow 33' to the upper end of the supply pipe 34. The lower end of the pipe 34 is connected to the discharge duct of the pumping mechanism 32 by an elbow 33a. The pumping mechanism 32 is preferably of the centrifugal type. Of this pumping mechanism, 36 indicates a suitable casting having a main portion shaped to form a re-

cess to accommodate the rotating member 37 and a tubular portion 38. The main portion of the casting 36 is provided with a flange 39, which is removably bolted to the end plate 11b, so that such portion and the plate form a casing for the rotating member 37. The recess for the rotating member 37 is shaped to provide a flow space or channel 39' for the liquid refrigerant, which space or channel terminates in a discharge conduit 40. The outer end of the conduit 40 registers with an opening formed in the end plate 11b, which opening, by means of the elbow 33a is connected to the lower end of the pipe 34. The intake for the rotating member 37 is provided axially thereof by an opening in the wall of the plate 11b, which opening registers with one end of a pipe 42; the other end of the pipe 42 leading through the bottom wall of the casing 11 and terminating at a point slightly above such wall for a purpose later to be set forth. The pipe 42 is adapted to convey the liquid refrigerant from the casing 11 to the rotating member 37, which forces it through the conduit 40, elbow 33a and pipe 34 to the distributing device 33. The main portion of the casting 36 is preferably formed within 100 the flange 39 with an annular recess 43 to receive an annulus 44, which closes the channel 39'. The rotating member comprises a disk 37' having on its inner face uniformly spaced vanes 45 and a circular plate 46 bridging the spaces between the vanes. Each vane 45 has inwardly converging side walls so arranged that (1) each side wall of each vane is parallel to and spaced from but relatively close to the opposed side wall of the next or adjoining vanes and (2) each space 110 extends at an angle of approximately 11½ degrees to a radius of the member which radius medially cuts the outer end of the space, the inner end of the space being forward of such radius with respect to the direction of rotation of the member 37. The disk 37' is secured to the reduced inner end of a shaft 47 by a nut 48. The shaft 47 extends through the tubular portion 38, being supported therein by suitable spaced anti-friction bearings; and the outer end of the shaft 120 47 is connected through a flexible coupling 49 to the shaft of an electric motor 50, mounted on a sub-base 1d. A sealing means 51' is provided inwardly of the inner shaft bearing between the shaft 47 and the opening in the wall of the main portion of the casting 36, to prevent leakage of 125 the liquid ammonia along the shaft. The tubular portion 38 forms a reservoir for a lubricant for the shaft bearings.

Of the oil separating means 11x, 51 indicates a plate extending across the bottom of the casing 11 in spaced relation thereto, being supported in such position by suitable blocks. The plate 51 engages the front and rear walls 11b, 11c, of the casing 11 and the longitudinal side edges of 130 the plate engage the side walls 11 of the latter, but these edges are roughened, serrated or notched to form openings 51a to permit any oil, which may collect in the liquid refrigerant from the compressor, to drain through these openings below the plate due to its high specific gravity relative to the ammonia. The bottom of the casing 11 is formed with an outlet which is connected to an oil sump 52 in which the oil collects. The sump 52 is provided with a valved drain pipe 53. The pipe 53 may be used to drain the case 1c of 145 ammonia, when desired. The inner end of the plate 51 is formed with an opening and this opening is provided with a suitable screen 54 which extends over the inlet end of the pipe 42. The 150

marginal portions of the screen are preferably inclined downwardly so as to elevate its central portion above the plate 51 to accommodate the pipe 42 which preferably extends upwardly beyond the latter and thus prevents any oil that may accumulate below the plate from flowing into the pipe 42.

55 indicates a hood for enclosing the float mechanism and adapted to protect the float 24a from any sudden fall or rise of the level of the liquid refrigerant due to starting or stopping of the pump mechanism or elevating means 12. The hood 55 comprises a sheet metal cylinder disposed horizontally axially of the member 20 and having an outer end wall 55a. The inner end of the cylinder preferably telescopes on to a reduced portion of the member 20, being secured thereon by friction or otherwise if desired. As shown, the hood 55 is semi-submerged in the liquid refrigerant when the latter is at its normal level, its lower portion being formed with a plurality of openings to admit the refrigerant and at a point in the upper portion of the hood (for example, its end wall) it is formed with a vent 56.

25 In the form of construction shown in Figs. 5 and 6, the means for elevating and distributing the liquid ammonia are of a different construction, as follows: 57 indicates a plurality of flexible members, such as chains uniformly spaced longitudinally of the casing 11 between its end walls 11b, 11c. These chains at their upper ends engage sprockets 58, by which they are driven and depend downwardly therefrom to either side of the cylinder 2a, preferably sliding on the latter and their lower portions are suspended or submerged in the liquid ammonia, below its level. Accordingly, when the chains are driven, the ammonia adheres to the chains and lodges in the spaces between its links and bars, and it is carried upwardly therewith and distributed on the walls of the cylinder 2a. The chains may be driven at a desired speed to convey sufficient ammonia to the upper portion of the cylinder to insure the necessary heat transfer as the surplus ammonia gravitates to the lower portion of the casing. When desired, the chains may be provided with buckets or flights. The sprockets 58 are fixed to a shaft 59 which is mounted at one end in a bearing provided on one end wall of the casing 11 (for example, the front end wall 11b). The other end of the shaft is similarly mounted in the other end wall and extends therethrough for connection with the shaft of an electric motor 60 suitably mounted on the support 1. In this arrangement, the inlet 3 extends upwardly to one side of the support for the motor 60.

61 indicates a trough provided on the upper portion of the cylinder 2a and extending longitudinally thereof between the runs of the chains. The trough serves to collect ammonia elevated by the chains and by means of openings formed in the trough walls the ammonia is distributed over the walls of the cylinder 2a.

Operation: in freezing a batch of the "mix" the driving means 8 are first started to set the agitating mechanism 6 in operation. Next, a measured quantity of the "mix" is introduced into the cylinder 2a through the inlet 2. Next, the switch (not shown) for the circuit for the motor 50 is closed. Upon starting of the motor 50, the pumping and distributing means are set in operation, the effect of which is to distribute the ammonia onto the walls of the cylinder. The ammonia flows over the cylinder walls as it gravitates to the lower portion of the evaporator enclosing cas-

ing 11, from which portion it is again pumped and distributed to the cylinder 2a. As the ammonia flows over the cylinder walls, rapid absorption of heat units from the "mix" results. This absorbed heat is carried away in the form of gas which rises to the upper portion of the evaporator enclosing casing through the spaces between the cylinder and casing and passes out through the suction pipe 13. The supply of ammonia from the distributor is sufficient to maintain a film or sheet of the liquid on the evaporator walls so long as the pump 50 is in operation, so that ample space is provided to permit of the separation and upward flow of the gas. When the "mix" is frozen to the desired temperature, the motor 50 is stopped. As this operation instantly cuts off the supply of ammonia to the distributing device and that portion of the ammonia in the distributor and flowing over the evaporator walls immediately gravitates to the lower portion below the evaporator 2, heat transfer is substantially immediately arrested. By continuing the operation of the agitating mechanism, the "mix" is whipped to secure the proper yield or over-run, following which it is discharged. When a new batch of "mix" is introduced into the cylinder 2a, the motor 50 is again started, which substantially instantly supplies the ammonia to the walls of the cylinder 2a.

From the foregoing description it will be seen that the liquid ammonia is substantially instantly applied to substantially the entire exterior surface of the cylinder 2a when the pump 37 is started, and when the pump 38 is stopped, the entire application of the ammonia thereto substantially instantly ceases. This permits positive control of the refrigeration and tends to speed the operations of freezing and whipping successive batches of the "mix". Also, as the liquid ammonia is discharged above the cylinder 2a and flows downwardly thereover, it continuously washes the walls of the latter, so that any and all gas that may form in pockets between these walls and the liquid flowing downwardly is dislodged from these walls by the flowing liquid and separated from the latter due to its movement, the effect of which is to insure rapid and uniform refrigeration or heat transfer over the entire cylinder. Since the scrapers 7 have a revolving speed of approximately 175 revolutions per minute, it will be seen that a very thin film of material is allowed to adhere to the interior of the inner surface of the cylinder 2a between adjacent scrapers as they traverse the cylinder wall before the next, rearward scraper engages therewith to remove it. Accordingly, the uniform application of the liquid ammonia to the exterior surface of the cylinder in conjunction with the operation of the scrapers is advantageous to insure a uniform, smooth frozen consistency of the "mix" wherein the ice crystals are finely and uniformly divided.

My construction is advantageous for the reason that discharge of the liquid ammonia from the space 10 is not dependent upon the generation of gas therein to expel the liquid ammonia or by operation of one or more valves, but it permits the liquid ammonia to gravitate or drain at all times to a point below the evaporator 2 so that danger of explosions, due to injection of hot water or steam into the container, is entirely eliminated. In other words, the liquid ammonia is applied to the evaporator mechanically and gravitates thereover, as contra-distinguished from a thermal or flooded system, for which reason the construc-

- tion is relatively simple, and the heat transfer is effectively and positively controlled to insure rapid as well as uniform cooling or freezing. In such construction and method of operation, it will be noted that no valves are required to be operated to effect complete freezing of each batch or the freezing of successive batches; also, since the liquid ammonia always flows over the evaporator in one direction and does not surge into and out of its enclosing casing, its supply and cut-off are positively controlled and time is saved in carrying out the successive steps in freezing each batch, as well as applying the liquid ammonia to each new batch to be frozen.
- 15 In my construction the evaporator enclosing casing, which serves as the accumulator for the supply of the volatile liquid refrigerant (and the evaporator which contains the material from which heat is to be extracted, constitute a unitary structure so arranged that the liquid refrigerant supply and the application thereof to the walls of the evaporator is within the casing separation of the gases from the liquid refrigerant is readily and automatically effected and no transfer of the refrigerant into and out of the casing is required. At the same time, during whipping of the "mix" or when the apparatus is not in use, the evaporator walls are devoid of heat transfer effect and the refrigerant supply is effectively insulated from external heat so that no waste of the refrigerant results from boiling thereof or due to frosting of exposed parts.
- It will also be noted that due to the circulation of the liquid refrigerant in an open space while in contact with the walls of the cylinder 2a, that gas pockets or bubbles generated by the absorption of heat are carried away from such walls as fast as such bubbles form and due to the fact that there is an unfilled flow space around these walls, the gas bubbles become automatically separated from the liquid and flow upwardly. As this flow space is enlarged, preferably progressively toward the top portion of the casing, the gas is drawn therefrom in a dry condition. This washing of the evaporator walls of the gas bubbles and separation thereof from the liquid prevent these bubbles from insulating the evaporator walls, and danger of the bubbles exploding and ejecting both the liquid and gas into the suction pipe is avoided. This process of applying the liquid refrigerant and carrying off the gas bubbles serves to increase the transfer of heat so that the freezing step is effected expeditiously.
- To those skilled in the art to which my invention relates, many changes in construction and widely differing embodiments and applications of the invention will suggest themselves without departing from the spirit and scope thereof. My disclosures and the description herein are purely illustrative and not intended to be in any sense limiting.
- What I claim is:
1. In a heat transfer and gas separating mechanism, the combination of a casing having insulated walls and forming a combined accumulator for a volatile liquid refrigerant and a gas separator; an automatically controlled supply means for the refrigerant; an evaporator for containing materials from which heat is to be extracted supported within said casing and in spaced relation to its walls and above the normal level of the refrigerant therein; and means for circulating the refrigerant within the casing into contact with the walls of said evaporator.
  2. In a heat transfer and gas separating mech-
  3. In a heat transfer and gas separating mechanism, the combination of a casing having insulated walls and forming a combined accumulator for a volatile liquid refrigerant and a gas separator; a suction connection leading from the upper portion of said casing; valved supply means for the refrigerant; an evaporator for holding materials from which heat is to be extracted within said casing and in spaced relation to its side walls and above the normal level of the refrigerant therein and supported in the end walls of said casing; and means for circulating the refrigerant within said casing into contact with the walls of said evaporator.
  4. In a heat transfer and gas separating mechanism, the combination of a casing having insulated walls and forming a combined accumulator for a volatile liquid refrigerant and a gas separator; a suction connection leading from the upper portion of said casing; valved supply means for the refrigerant; an evaporator for holding materials from which heat is to be extracted within said casing and in spaced relation to its side walls and above the normal level of the refrigerant therein and supported in the end walls of said casing; the heads for said evaporator being exposed outside the end walls of said casing, one of said heads being provided with a material inlet and one of said heads being provided with a valved discharge outlet; and means for circulating the refrigerant within said casing into contact with the walls of said evaporator.
  5. In a heat transfer and gas separating mechanism, the combination of a casing having insulated walls and forming a combined accumulator for a volatile liquid refrigerant and a gas separator; a suction connection leading from the upper portion of said casing; valved supply means for the refrigerant; an evaporator for containing materials from which heat is to be extracted supported within said casing and in spaced relation to its walls and above the normal level of the refrigerant therein; and means for circulating the refrigerant within said casing substantially in the form of a film into contact with the walls of said evaporator.
  6. In a heat transfer and gas separating mechanism, the combination of a casing having insulated walls and forming a combined accumulator for a volatile liquid refrigerant and a gas separator; a suction connection leading from the upper portion of said casing; valved supply means for the refrigerant; an evaporator for containing materials from which heat is to be extracted supported within said casing and in spaced relation to its walls and above the normal level of the refrigerant therein; and means for elevating the refrigerant within said casing and distributing it onto the walls of said evaporator substantially in the form of a film.
  7. In a heat transfer and gas separating mechanism, the combination of a casing having insu-

- lated walls and forming a combined accumulator for a volatile liquid refrigerant and a gas separator; a suction connection leading from the upper portion of said casing; valved supply means 5 for the refrigerant; an evaporator for containing materials from which heat is to be extracted supported within said casing and in spaced relation to its walls and above the normal level of the refrigerant therein; said casing being shaped to 10 enlarge the space above said evaporator; and means for circulating the refrigerant substantially in a film in contact with the walls of said evaporator and permitting it to gravitate thereover.
15. 8. In a heat transfer and gas separating mechanism, the combination of a casing having insulated walls and forming a combined accumulator for a volatile liquid refrigerant and a gas separator; a suction connection leading from the 20 upper portion of said casing; valved supply means for the refrigerant; an evaporator for containing materials from which heat is to be extracted supported within said casing and in spaced relation to its walls and above the normal level of the refrigerant therein; said casing being shaped to 25 enlarge the space above said evaporator; and means for circulating the refrigerant above said evaporator and permitting it to gravitate over its walls.
30. 9. In a heat transfer and gas separating mechanism, the combination of a casing having insulated walls and forming a combined accumulator for a volatile liquid refrigerant and a gas separator; a suction connection leading from the 35 upper portion of said casing; valved supply means for the refrigerant; an evaporator for containing materials from which heat is to be extracted supported within said casing and in spaced relation to its walls above the normal level of the refrigerant therein; means for circulating the refrigerant into contact with the walls of said 40 evaporator; and means in said casing for separating oil from the refrigerant.
10. In a heat transfer and gas separating mechanism, the combination of a casing having insulated walls and forming a combined accumulator for a volatile liquid refrigerant and a gas separator; a suction connection leading from the 45 upper portion of said casing; valved supply means for the refrigerant; an evaporator for containing materials from which heat is to be extracted supported within said casing and in spaced relation to its walls above the normal level of the refrigerant therein; means for circulating the refrigerant into contact with the walls of said 50 evaporator; and means below the level of the refrigerant within said casing and located in said casing for separating oil from the refrigerant.
11. In a heat transfer and gas separating mechanism, the combination of a casing having insulated walls and forming a combined accumulator for a volatile liquid refrigerant and a gas separator; a suction connection leading from the upper 55 portion of said casing; valved supply means for the refrigerant; an evaporator for containing materials from which heat is to be extracted supported within said casing and in spaced relation to its walls and above the normal level of the refrigerant therein; means for circulating the refrigerant within said casing into contact with the 60 walls of said evaporator; and means below the level of the refrigerant in said casing for separating oil from the refrigerant, said separating means comprising a plate disposed in spaced relation to the bottom of said casing and engaging the 65 sides thereof, one edge of said plate being formed with notches.
12. In a heat transfer and gas separating mechanism, the combination with a support provided with a case having insulated walls; of a casing having insulated walls and forming a combined accumulator for a volatile liquid refrigerant and a gas separator; the lower portion of said insulated casing being enclosed in said case; a suction connection leading from the upper portion of said casing; valved supply means for the refrigerant; an evaporator for containing materials from which heat is to be extracted supported within said casing and in spaced relation to its walls and above the normal level of the refrigerant therein; and means for circulating the refrigerant within said casing in contact with the walls of said evaporator. 80
13. In a heat transfer and gas separating mechanism, the combination of a casing having insulated walls, said casing being elongated vertically and forming a combined accumulator for a volatile liquid refrigerant and a gas separator; a suction connection leading from the upper portion of said casing; valved supply means for the refrigerant; an evaporator for containing materials, from which heat is to be extracted, supported within the upper portion of said casing above the normal level of the refrigerant therein; and means for circulating the refrigerant within said casing 95 in contact with the walls of said evaporator; the upper portion of said casing being spaced from the walls of said evaporator to permit flow of the liquid refrigerant through the space in contact with said walls and separation from the liquid of 100 gases due to absorption of heat.
14. In a heat transfer and gas separating mechanism, the combination of a casing having insulated walls and forming a combined accumulator for a volatile liquid refrigerant and a gas separator; a suction connection leading from the upper portion of said casing; valved supply means for the refrigerant; an evaporator for containing materials from which heat is to be extracted supported within said casing and in spaced relation to its walls and above the normal level of the refrigerant therein; a distributing device in said casing and above said evaporator for discharging the refrigerant onto the walls of said evaporator; and means for conveying the refrigerant in the 115 accumulator to said device. 120
15. In a heat transfer and gas separating mechanism, the combination of a casing having insulated walls and forming a combined accumulator for a volatile liquid refrigerant and a gas separator; a suction connection leading from the upper portion of said casing; valved supply means for the refrigerant; an evaporator for containing materials from which heat is to be extracted supported within said casing and in spaced relation to its walls and above the normal level of the refrigerant therein; and means having portions submerged in the refrigerant within said casing below its level for conveying it to the upper portion of 130 said evaporator.
16. In a heat transfer and gas separating mechanism, the combination of an evaporator for containing materials from which heat is to be extracted; an insulated casing forming a combined accumulator for a volatile liquid refrigerant, a 145 gas separator and an enclosure for said evaporator; said evaporator being disposed above the normal level of the refrigerant in said casing and in spaced relation to the walls thereof for permitting separation of the gas from the liquid refrigerant. 150

erant during circulation thereof; a suction connection leading from the upper portion of said casing; valved supply means for the refrigerant; and means for circulating the refrigerant within 5 the casing into contact with the walls of said evaporator.

17. In a heat transfer and gas separating mechanism, the combination of an evaporator for containing materials from which heat is to be extracted; an insulated casing forming a combined 10 accumulator for a volatile liquid refrigerant, a gas separator and an enclosure for said evapora-
